DESIGN FOR A PACKAGE OR SIMILAR ARTICLE

Charles Weiner, Chicago, Ill., assignor to Chicago Printed String Co., Chicago, Ill., a corporation
of Illinois

Application February 27, 1933. Serial No. 47,338

Term of patent 7 years

To all whom it may concern:

Be it known that I, CHARLES WEINER, a citizen of the United States, and a resident of the city of Chicago, county of Cook, and State of Illinois,
have invented a new, original, and ornamental Design for a Package or Similar Article, of which the following is a specification, reference being had to the accompanying drawing forming a part thereof.

On the drawing:

The figure illustrates an isometric view of the package or similar article, embodying my invention.

I claim:

The ornamental design for a package or a similar article, as shown.

CHARLES WEINER.
